UNITED STATES PATENT OFFICE.

MILADORE A. BUTTON, OF LAMAR, MISSOURI.

CIRCUIT-CLOSER.

1,148,750.

Specification of Letters Patent. Patented Aug. 3, 1915.

Application filed September 4, 1914. Serial No. 860,245.

To all whom it may concern:

Be it known that I, MILADORE A. BUTTON, citizen of the United States, residing at Lamar, in the county of Barton and State 5 of Missouri, have invented certain new and useful Improvements in Circuit-Closers, of which the following is a specification, reference being had to the accompanying drawings.

10 This invention relates to certain improvements in circuit closers and has relation more particularly to a device of this general character especially designed and adapted for use in connection with low tension dual ignition for motors or the like; and an object of the invention is to provide 15 a device of this general character having novel and improved means whereby the operation thereof by unauthorized persons is 20 effectually guarded against.

Furthermore, it is an object of the invention to provide a device of this general character adapted to be inclosed within a casing and having means of a novel and 25 improved character whereby access within the casing is prevented during the period the closer is adjusted into open or break position.

The invention consists in the details of 30 construction and in the combination and arrangement of the several parts of my improved circuit closer whereby certain important advantages are attained and the device is rendered simpler, less expensive 35 and otherwise more convenient and advantageous for use, all as will be hereinafter more fully set forth.

The novel features of the invention will be 40 carefully defined in the appended claims.

45 In order that my invention may be the better understood, I will now proceed to describe the same with reference to the accompanying drawings, wherein—

Figure 1 is a sectional view taken through 45 a circuit closer constructed in accordance with an embodiment of my invention; Fig. 2 is a top plan view of the device as herein embodied; Fig. 3 is a view, partly in bottom plan, with the base of the casing re- 50 moved, together with the contacts coacting therewith; Fig. 4 is a view in top plan of the base portion of the casing illustrating the contacts; Fig. 5 is a fragmentary feature, partly in elevation, and partly in section, illustrating in detail views the per- 55 mutation mechanism herein included; Fig.

6 is a view partly in elevation and partly in section of the lever or pawl herein included; Fig. 7 is a view in plan of an expandable member herein embodied; and em- 60 ployed in connection with the permutation mechanism; Fig. 8 is a view in top plan of a slightly modified form of the invention.

As disclosed in the accompanying drawings, 1 denotes a cylindrical casing having 65 one face open, said open face being adapted to be closed by the cover member 2 provided with an annular flange adapted to overlie the periphery of the casing 1 and detachably engage said casing through the me- 70 dium of conventional threads. At substantially its axial center, the cover 2 is provided with the sleeve 3 adapted to be disposed within the casing 1 to a predetermined extent and in which is rotatably mounted 75 the spindle 4 adapted to project exteriorly of the casing when in applied position and to such projected portion of the spindle is suitably affixed an operating knob 5 whereby requisite axial rotation may be imparted 80 to the spindle 4, the knob 5 is provided with the annular dial plate 6 adapted to move therewith and provided with the graduations 7 coacting with suitable demarcations 8, for a purpose which will hereinafter be 85 self-evident.

It is to be observed that the outer or free marginal portion of the dial 6 is adapted to engage the inner periphery of the annular flange 9 produced on the outer face of the 90 cover 2 in concentric relation with the sleeve 3.

The knob 5 affords a means whereby the desired axial rotation may be imparted to the spindle 4 by hand, although I have 95 found in practice that under certain conditions and as illustrated in Fig. 8, the knob 5 may be omitted and the dial 6 be carried by the spider 5^a operatively engaged with the spindle and the dial provided with the 100 radial extension 10, adapted to be engaged by a foot which, in connection with motor vehicles, has proven to be of especial benefit.

Fixedly secured to the inner extremity of the spindle 4 is a disk 11 preferably of 105 brass, while 12 denotes a plurality of disks also preferably of brass loosely mounted upon the spindle 4 and clamping therebetween the disks 14 of fiber or other non-conductive material, the requisite engage- 110 ment between the disks 12 and 14 being maintained, as herein disclosed, through the

medium of the annular member 15 surrounding the sleeve 3 and interposed between the uppermost disk 12 and the retaining member 16 of fiber or other non-conductive material also surrounding the sleeve 3 and in contact with the inner surface of the cover 2, said washer being provided with spring tongues 17 serving in a manner and for a purpose which is believed to be self-evident.

10 The disks 14 serve as the tumblers for a permutation mechanism and are provided in their peripheries with the notches 18 adapted to be brought in requisite alinement by 15 proper manipulation of the spindle 4, said disks 14 being provided with the laterally disposed pins 19 coacting in a manner which is believed to be self-evident.

10 The depth of the notches 18 are such as to 20 permit, when in alined relation, of contact between the peripheries of the disks 14 and the head 20 of the substantially U-shape pawl or lever 21 of conductive material. As herein embodied, the stems of the pawl or 25 lever 21 are rotatably supported by the contact post 22, the head 20 of the pawl or lever 21 being normally maintained in engagement with the peripheries of the disks 14 under the influence of the spring 23 herein 30 disclosed as a coil spring surrounding said contact post 22 and having one extremity anchored thereto while the opposite extremity of such spring is suitably connected with the pawl or lever 21.

35 As herein embodied, the contact post 22 is operatively supported by the retaining member 16 and the annular member 24 of fiber or other non-conductive material. The annular member 24 is provided with the contact 40 plates 25 provided with the binding posts 26 whereby the desired electrical connection through the medium of the conductors *c* may be had with the battery and magneto. The casing 1 is provided with suitable 45 openings 27 through which the conductors *c* are directed. Coacting with the contact plates 25 is the brush 28 projecting from the lower extremity of the spindle 4 and maintained in operative position thereon through 50 the medium of the clamping nut 29, said plate 25 having the extensions 25^a projecting inwardly of the member 24 and with which the brush 28 engages.

55 The contact post, hereinbefore referred to, has its lower extremity in engagement with the contact plate 30 provided with a binding post 31 whereby a connection may be had through the conductor *c'* with the coil, said casing being provided with a suitable 60 opening 32 through which said conductor is directed. The member 24 is also provided with a plate 33 projecting inwardly of the member 24 and on which the brush 28 is adapted to rest when the spindle 4 is adjusted into off position.

Fixedly secured to the disk 11 is a cam member 34 of fiber or other non-conductive material provided with a lateral pin 35 adapted to coact with the pin of the adjacent disk 14 whereby it will be readily perceived that the tumblers afforded by the disks 14 are caused to properly operate, and it will also be observed that the cam 34 serves, upon the axial rotation of the spindle 4, to raise the head of the pawl or lever 21 from within the alined notches 18.

70 It is to be observed that the low point *a* of the cam 34 is of such an extent as to permit an independent movement thereof under the influence of the spindle 4 in order that the requisite engagement or contact may be had as required with either of the contact plates 25. In order that it may be readily determined which of the plates 25 the brush is in contact with or to determine its position upon the plate 33, the demarcations, hereinbefore referred to, have positioned in close proximity thereto suitable identities or indications 35'.

75 When the pawl or lever 21 is adjusted 80 from within the notches 18, the head 20 is caused to engage an inwardly disposed projection 36 carried by the inner wall of the casing 1 whereby it will be readily perceived that the cover member 2 is effectively held against movement which would result in its disengagement or separation from the casing. By this arrangement, it will be readily perceived that access within the casing 1 by 85 unauthorized persons is effectually guarded 90 against.

95 In order to afford a positive stop for the dial 6 when the same has been properly adjusted relative to the plates 25, which adjustment is determined by the arrow 37, I 100 find it of advantage to produce in the dial 6, suitable recesses or openings 38 in which is adapted to be automatically projected the spring pressed locking member 39 carried by the cover member 2 and operating in 105 a manner which is believed to be self-evident. It is also thought to be obvious that when it is necessary to adjust the dial 6 in order to properly set the disks 14 and the cam 34, the member 38 is adjusted away 110 from the dial.

115 From the foregoing description, it is 120 thought to be obvious that a circuit closer constructed in accordance with my invention is of an extremely simple and comparatively inexpensive nature and is particularly well adapted for use by reason of the convenience and facility with which it may be assembled, and it will also be obvious that 125 my invention is susceptible of some change and modification without material departure from the principles and spirit thereof and for this reason I do not wish to be understood as limiting myself to the precise arrangement and formation of the sev- 130

eral parts herein shown in carrying out my invention in practice.

I claim:

1. A circuit closer comprising a casing, a plurality of contacts mounted therein, a spindle projecting within the casing and adapted to engage certain of the contacts, and a permutation mechanism within the casing under control of the spindle, said mechanism including a movable member electrically connected with a second contact and adapted to electrically engage the spindle upon a predetermined adjustment of the permutation mechanism.
2. A circuit closer comprising a casing, a plurality of contacts mounted therein, a spindle projecting within the casing and adapted to engage certain of the contacts, a permutation mechanism within the casing under control of the spindle, said permutation mechanism including a pawl member electrically connected with a second contact and adapted to electrically engage the spindle upon a predetermined adjustment of the permutation mechanism, said casing having one face open, a cover member for the open face of the casing, and means carried by the casing coacting with the pawl whereby said cover member is maintained against removal when the pawl is adjusted in open position.
3. A circuit closer comprising a casing, a plurality of contacts mounted therein, a spindle projecting within the casing and adapted to engage certain of the contacts, and a permutation mechanism within the

casing under control of the spindle, said mechanism including a movable member electrically connected with a second contact and capable of electrical connection with the spindle upon a predetermined adjustment of the permutation mechanism, said spindle being capable of limited axial rotation independently of the permutation mechanism when in locked adjustment whereby the spindle may be brought in contact with each of its coacting contacts.

4. A circuit closer comprising a casing, a plurality of contacts mounted therein, a spindle projecting within the casing and adapted to engage certain of the contacts, and a permutation mechanism within the casing under control of the spindle, said mechanism including a movable member electrically connected with a second contact and capable of electrical connection with the spindle upon a predetermined adjustment of the permutation mechanism, said spindle being capable of limited axial rotation independently of the permutation mechanism when in locked adjustment whereby the spindle may be brought in contact with either of its coacting contacts, said spindle being provided with means for imparting axial rotation thereto.

In testimony whereof I hereunto affix my signature in the presence of two witnesses.

MILADORE A. BUTTON.
